FIGURE 1

FIGURE2 FIGURE3

A technical diagram showing a cross-section of a coil assembly. The assembly is contained within a rectangular frame. On the left side, there is a vertical column of five circular components, labeled '14' with an arrow. On the right side, there is another vertical column of five circular components, also labeled '14' with an arrow. Between these two columns, there are two sets of vertical lines labeled '16' with arrows, representing the slots between the core legs. On the far right, there is a vertical column of five circular components, labeled '15' with an arrow. Below the frame, there are two sets of curved lines labeled '17' with arrows, representing the ends of the coil wires.

UNITED STATES PATENT OFFICE

MALVIN LICHTER, OF NEW YORK, N. Y., ASSIGNOR TO MALVIN LICHTER INC., A CORPORATION OF NEW YORK

MECHANICAL MEMORANDUM AND METHOD OF MAKING THE SAME

Application filed August 13, 1928. Serial No. 299,274.

My invention relates to mechanical memorandums and methods of making the same. More particularly stated, my invention comprehends a mechanical memorandum in which a stationary part is associated with a number of movable members each adjustable at the will of the operator, and associated with graphic legends or indicating marks, so that the operator, by shifting the movable members into different positions relatively to the stationary part can cause the device as a whole to indicate certain predetermined memoranda, such as different items of merchandise concerning which the operator desires to be reminded.

My invention relates to structural improvements in mechanical memorandums of the kind just mentioned, for improving the efficiency thereof, by giving to the construction an arrangement of the various parts certain points of mechanical advantage.

My invention further relates to an improved method for shaping certain of the parts and for fitting them into position, with a minimum expenditure of time and labor.

Further purposes and objects of my invention are brought out in the descriptive matter set forth below.

Reference is made to the accompanying drawings forming a part of this specification, and in which like reference characters indicate like parts throughout the several figures.

Figure 1 is a fragmentary plan of one of the blanks used in making my improved mechanical memorandum, and it is cut from sheet material, preferably card-board or the like.

Figure 2 is a fragmentary plan of another blank used in the construction of my device, and having the form of a serrated strip made of sheet material, such as card-board.

Figure 3 is a fragmentary plan of still another blank having the form of a serrated strip made of sheet material such as card-board, and used in my construction.

Figure 4 is a fragmentary plan showing the blank appearing in Figure 1, and a pair of strips of the kind shown in Figure 2, as assembled and fitted together during the manufacture of my device.

Figure 5 is a fragmentary plan indicating a further step in manufacture, the two strips just mentioned having been cut into small pieces, each having the form of a slide.

Figure 6 is a plan view of the finished article, certain parts being broken away.

Figure 7 is a section on the line 7—7 of Figure 6, looking in the direction indicated by the arrows.

A blank 7, made of sheet material such as card-board, paste board, celluloid, thin leather or leatheroid, tough paper or the like, is cut out and formed as indicated more particularly in Figure 1.

The blank 7 is provided with flanges 8 and 9, and with end flaps 10 and 11, these all being preferably integral as shown.

The blank is further provided with score lines 12, 12, 13, 13, and is adapted to be folded or bent, upon these score lines.

The blank is further provided with two rows of circular openings 14 and 15, coinciding in general direction with the score lines 12, 12, and is further provided with two rows of openings, 16, 17, carried by the flanges 8 and 9, and having the form of arcuate slots. The purpose of the openings 14, 15, 16, and 17, is explained below.

In connection with the blank 7 I use two smaller blanks having the form of strips 18 and 19, of the kind shown in Figures 2 and 3, respectively, and made of sheet material, in this instance card-board. During the manufacture of my device these two strips are each connected with and fitted upon the blank 7, as indicated in Figure 4, but in the finished article the two strips no longer appear as strips, they having been cut into pieces each having the form of a slide, as may be understood by contrasting Figure 4 with Figures 5 and 6.

The strip 18 is provided with tongues 20, 21 and 22 integral with it, the tongues 20 being somewhat longer than the tongues 21, and the tongues 22 being of substantially the same length as the tongues 21.

The strip 19 is provided with tongues 23 exactly like the tongues 22, and is further provided with tongues 24, having the same

form as the tongues 21 and being of the same length thereof.

In practice the two strips 18 and 19 are each laid upon the blank 7, and for the time being secured thereto as above described. For this purpose the tongues 20 and 21 are tucked through the openings 16, having the form of slots, and the tongues 22 are tucked through the circular openings 14. Similarly the tongues 23 are tucked through the circular openings 15, and the tongues 24 are tucked through the slots 17.

This leaves the blank 7 with the strips 18 and 19 in the condition indicated in Figure 4.

Next the two strips 18 and 19 are each cut crosswise, so as to form from it a large number of separate pieces 25 and 26, each having the form of a slide, the slides being arranged in two rows parallel with each other, as indicated in Figure 5.

The step of cutting the strips crosswise is preferably effected by means of cutting machinery adapted for the purpose, but may be done by hand. The main requirement in this respect is that each strip shall be severed in a sufficient number of places to convert it into slides, care being exercised to make the cuts in the right places in order to render the slides of proper form.

The next step in manufacture is to bend the flanges 8 and 9 upon the score lines 12, 12; and this done, to next bend over the end flaps 10 and 11, so as to cause them to overlap the adjacent portions of the flanges 8 and 9.

A guide sheet 27, made of card-board or other appropriate sheet material, is next laid in position, so that its ends overlap the adjacent or inner portions of the end flaps 10 and 11, the sides of the guide sheet overlapping the exposed portions of the tongues of the slides 25 and 26. Thus the two edges of the guide sheet 27 slightly overlap and engage directly the adjacent portions of the flanges 8 and 9.

The guide sheet 27 is provided with circular holes 28, so located that with the guide sheet in position these openings are in registry with the tongues of the slides 22, in this instance four in number, as indicated in the upper left-hand corner of Figure 6.

Up to this stage in the manufacture there is no occasion for the use of any adhesive or of any special fastening mechanism, aside from the respective forms given to the various parts, and the connection of the various parts, as thus fitted together.

The next step of manufacture is to lay upon the other parts, as partially assembled in the relation just described, a face sheet 29. This face sheet is made of card-board, paper or other appropriate sheet material, and is provided with circular holes 30 so formed and positioned as to register with the holes 28 above described with reference to the guide

sheet 27, and thus to register with the tongues of the adjacent slides.

The face sheet 29 has a pair of oppositely disposed edge portions 31 and 32, integral with it. These edge portions 31 and 32, shown more particularly in Figure 7, are glued or pasted firmly down upon the underlying portions of the flanges 8 and 9, and are thus firmly secured in position.

The only pasting or gluing required in my device or in the manufacture thereof, is between these edge portions 31 and 32 and the adjacent underlying portions of the flanges 8 and 9. No pasting or gluing is necessary for the guide sheet 27, it being held in position by fitting into and among the other parts.

The face sheet 29 is provided with graphic legends, as shown, such as the words Butter, Fruit, Flour, Tea, Tomatoes, etc., representing the various items concerning which the operator, usually a housewife, seeks to be reminded. These legends are so located as to be in immediate association with the various slides, and the slides are so arranged and co-related with other parts that, by drawing out any number of the slides, appropriate indications can be made.

It will be noted from Figures 2 and 6 that some of the slides are provided with longer tongues than others, the slides with the long tongues being provided with legends 1 and 2. These particular slides are used as indicated in the upper left-hand corner of Figure 6. By pulling either of the slides outwardly the appropriate legend 1 or 2 is exposed to view through the holes 28 and 30. The face sheet 29 has in its upper left-hand corner, according to Figure 6, a number of legends Baking-Powder 1, Yeast 2; Bacon 1, Ham 2; Beans 1, Lentils 2; Bread 1, Crullers 2. These last mentioned legends are so arranged that the various items represented by the legends can be indicated by the positions into which the slides are drawn out.

The various upper slides shown each has only two normal positions; one being when the slide is pushed inwardly to the limit of its travel, so as to register no indication, the other being when the slide is drawn outwardly to the limit of its travel, in which event it makes only a single indication, this indication being associated with a single one of the various legends above mentioned.

My device being now practically completed, the last step is to make a hole 33 through it at its top, to facilitate hanging it upon a nail or a hook. This hole can be made by a punch applied to the finished article; or may, if desired, be produced by perforating the various cardboard members before they are assembled.

The operation of my device may be understood from the foregoing description. The device as a whole serves the purpose of a mechanical memorandum, and with the slides once arranged to make appropriate indica-

tions of the items concerning which the operator desires to be reminded, it will stay in that position for any length of time.

The operator, in using the mechanical memorandum, first pushes all of the slides inwardly, the net result being that for the moment the memorandum registers no indications. Next the various slides, or such of them as are required, are drawn out as above described, so as to make the appropriate indication.

I do not limit myself to the particular steps of the method above described, or to the precise mechanism illustrated and described, the scope of my invention being commensurate with my claims.

Having thus described my invention, what I claim as new and desire to secure by Letters Patent is as follows:

1. A mechanical memorandum comprising a body portion of sheet material provided with flanges bent back upon it and further provided with end flaps bent to overlap portions of said flanges in order to hold said flanges in position, said body portion being provided with openings and with slots, and a plurality of separate slides each provided with a portion extending through one of said openings and one of said slots, each slide being thus supported upon said body portion and movable by hand relatively thereto so as to enable one of said slides to be distinguished from others by the position it occupies, said body portion being further provided with indicating marks, so positioned relatively to said slides as to be easily identified by aid of said slides when said slides occupy certain predetermined positions.

2. The method herein described, of making mechanical memorandums, which consists in preparing a body member of sheet material, providing the same with means for slidably supporting a number of separate slides movable by hand, applying to said body member a strip of sheet material provided with portions engaging said body member so as to hold said portions of said strip, cutting said strip into a number of separate slides, and providing means for enabling said slides, by occupying different normal positions, to make indications associated with items to be called to mind.

3. The method herein described, of making up mechanical memorandums, which consists in preparing a body member of sheet material, providing said body member with openings for slidably supporting a number of separate slides, applying to said body member a strip of sheet material provided with tongues extending through said openings, cutting said strip into a number of separate pieces, each piece being a slide provided with portions extending through said openings, and providing means for enabling said slide, when moved by hand into different positions,

to register indications associated with items to be called to mind.

4. The method herein described, of making mechanical memorandums, which consists in preparing a body member of sheet material having flanges bent back upon it, said flanges being provided with openings, forming a strip of sheet material provided with portions extending through said opening, and cutting said strip into a plurality of separate pieces, each provided with portions extending through some of said openings, and providing means for enabling said slides, by occupying different positions relative to said body member, to make indications associated with items to be called to mind.

5. A mechanical memorandum comprising a body portion of sheet material, and a plurality of slides carried by said body portion and movable relatively thereto, each slide having two extreme normal positions and an intermediate normal position, and indicating mechanism carried by said body portion and associated with said slides, for making a plurality of separate indications equal to the number of separate normal positions of said slide.

6. A mechanical memorandum comprising a body portion of sheet material provided with flanges bent back upon it and further provided with end flaps bent to overlap portions of said flanges in order to confine said flanges, a guide sheet engaging said end flaps, and a face sheet covering said guide sheet and engaging said flanges and said end flaps, and indicating mechanism carried by said body portion, for the purpose of indicating items to be called to mind.

7. A mechanical memorandum comprising a body portion of sheet material provided with flanges bent back upon it and further provided with end flaps bent to overlap portions of said flanges in order to confine said flanges, means for securing said end flaps, and a plurality of separate slides carried by said body portion and extending between said body portion and said flanges, said slides being movable into different positions for the purpose of registering indications.

Signed at New York city, in the county of Bronx and State of New York, this ninth day of August, 1928.

MALVIN LICHTER.
